CAR-END PLATFORM BUFFING MECHANISM

Roland J. Olander, Chicago, Ill., assignor to W. H. Miner, Inc., Chicago, Ill., a corporation of Delaware

Application August 25, 1945, Serial No. 612,614

10 Claims. (Cl. 213—222)

1

This invention relates to improvements in car-end platform buffing mechanism for railway cars.

One object of the invention is to provide a buffing mechanism including the usual end platform, buffer face plate, and spring resisted side stems for supporting the face plate from the platform, wherein the buffer side stems are made readily removable without disturbing the other parts of the mechanism by providing the buffer face plate with an opening through which the side stem may be bodily withdrawn, and providing detachable means for anchoring the buffer stem to the face plate which normally obstructs the opening through which the stem is removable.

Other objects of the invention will more clearly appear from the description and claims herein-after following.

In the drawing forming a part of this specification, Figure 1 is a fragmentary top plan view of a buffing device for railway cars embodying my invention, certain parts being broken away to show one of the buffer stems in plan. Figure 2 is a longitudinal vertical sectional view, corresponding substantially to the line 2—2 of Figure 1. Figure 3 is a disassembled view of the separated parts at the front end of the mechanism, showing the retainer pin in side elevation, the face plate in vertical section, supporting bracket in side elevation, and the front end portion of the buffer side stem in side elevation. Figure 4 is a front elevational view of a portion of the buffer face plate. Figure 5 is a detailed, perspective view of the supporting bracket for the buffer side stem.

Referring to the drawing, my improvement is shown in connection with a well-known type of buffing mechanism including the usual end platform 10 of a passenger car, having a central pocket 11 in which the friction shock absorber 12 of the buffing mechanism is accommodated, and a central buffer stem 13 engaging the friction shock absorber. The end platform is provided with the usual opening 14 through which the central buffer stem extends and in which it is guided. At opposite sides of the central buffer stem, the platform 10 is provided with the usual lengthwise extending openings 15—15 through which the buffer side stems extend and rear supporting members or brackets 16—16 also provided with guide openings for guiding the buffer side stems.

In carrying out my invention, I provide broadly a buffed face plate A supported by a pair

2

of spring opposed side stems B—B; and a pair of supporting brackets C—C seated over the front ends of the stems B—B, the buffer face plate being provided with openings D—D therethrough, through which the buffer side stems may be passed, and which openings are blocked by the brackets C—C to preclude removal of the side stems.

The buffer face plate A, which is supported forwardly of the platform 10 by the side stems B—B, comprises a vertical front wall 17, and top and bottom, rearwardly projecting, horizontal flanges 18 and 19. At opposite sides, I provide the face plate A with the openings D—D, which are of square outline and extend through the wall 17 and are respectively in alignment with the two buffer side stems. The openings D—D are of such a size as to permit the buffer stems to pass freely therethrough in lengthwise direction. As seen in Figure 2, each opening D has the top and bottom sides thereof spaced appreciably from the flanges 18 and 19 of the face plate A, thus providing abutment face portions 20—20 above and below the opening.

The buffer side stems B—B, which are disposed at opposite sides of the platform 10, are of like design. Each stem comprises a cylindrical, rod-like rear end section or shank 21 and an enlarged front end section 22 of square cross section. A shoulder 23 is thus provided between the front end section 22 and the shank section 21. At the extreme front end thereof, the section 22 has a vertical pin receiving opening 24 extending therethrough. Each buffer side stem B is provided with the usual spring 25 which surrounds the stem and bears at its front and rear ends respectively on a collar 26 on the section 21 of the stem, abutting the shoulder 23, and a collar 27 on the rear end of the section abutting the bracket 16 of the platform 10. Each stem also has the usual retaining nut 28 at the rear end thereof which abuts the rear side of the bracket 16 and limits forward movement of the stem B and the attached buffer face plate A.

The supporting bracket C—C are of like design, each bracket being in the form of a U-shaped member having a vertically extending transverse front wall 29 and rearwardly projecting, top and bottom, vertically spaced flanges 30 and 31 extending from the wall 29. The bracket C is of such a vertical height that it practically fills the opening between the top and bottom flanges 18 and 19 of the face plate A and is provided with a forwardly projecting central lug 32, on the wall 29, which is of square cross

section and substantially fits the square opening D at the corresponding side of the face plate A. The projecting lug 32 preferably has its front face flush with the front surface of the wall 17 of the face plate. The flanges 30 and 31 are 5 provided with vertically aligned openings 33-33 therethrough to receive a pin 34 which serves to connect the side stem to the bracket C and to the face plate, the latter being provided with aligned openings 35-35 in the flanges 18 and 19 10 thereof to accommodate the pin.

In the assembled condition of the parts of the buffer mechanism, as shown in Figures 1 and 2, the forward ends of the buffer side stems B-B 15 are secured to the face plate A by the pins 34-34 which extend through the openings 35-35 of the face plate, the openings 23-23 of the supporting brackets C-C and the openings 24-24 of the side stems B-B, thereby holding the brackets C-C in place and mounting the face plate for 20 pivotal movement with respect to each side stem.

To remove either buffer side stem B, the pin 34 is disengaged from the stem and bracket C, and the stop nut 28 removed from the rear end of the stem. The supporting bracket C and the buffer stem are then pushed inwardly as a unit to such an extent that sufficient clearance is provided rearwardly of the buffer face plate to permit detachment of the bracket C from the stem. After the bracket C has been detached, the buffer stem is withdrawn, through the opening D of the buffer face plate A by passing the stem lengthwise through said opening in forward direction. In applying the buffer stem, the procedure is substantially the reverse of that followed in removal thereof.

I claim:

1. In a buffering mechanism for a railway car including an end platform, the combination with a buffer face plate; of a buffer stem supporting said face plate from the end platform, said face plate having an opening therethrough in alignment with the buffer side stem, said opening being of a size to permit lengthwise withdrawal of the buffer side stem therethrough; a detachable 45 supporting bracket blocking said opening; and a pin pivotally connecting the buffer side stem to said bracket and face plate for relative swinging movement in a horizontal plane, said pin extending through the face plate and bracket and the 50 forward end of the buffer stem.

2. In a buffering mechanism for a railway car including an end platform, the combination with a buffer face plate; of a lengthwise extending buffer side stem supporting said face plate from the end 55 platform, said face plate having an opening therethrough in alignment with the buffer side stem, said opening being of a size to permit lengthwise withdrawal of said stem therethrough; and a member detachably fixed to the face plate and 60 closing the opening of the face plate to block removal of the buffer side stem.

3. In a buffering mechanism for a railway car including an end platform, the combination with a buffer face plate; of a lengthwise extending buffer side stem supporting said face plate from the end platform, said face plate having an opening therethrough in alignment with the buffer side stem, said opening being of a size to permit lengthwise withdrawal of said stem therethrough; and a member detachably fixed to the front end 70 of the buffer stem, said member being of a size to block said opening and prevent removal of the buffer side stem through said opening.

4. In a buffering mechanism for a railway car in-

cluding an end platform, the combination with a buffer face plate; of a lengthwise extending buffer side stem supporting said face plate from the end platform, said face plate having an opening therethrough in alignment with the buffer side stem, said opening being of a size to permit lengthwise withdrawal of said stem therethrough; and a member engaged over the front end of the buffer side stem and detachably fixed thereto, said member being of a size to block said opening and prevent removal of the buffer side stem through said opening.

5. In a buffering mechanism for a railway car including an end platform, the combination with a buffer face plate; of a lengthwise extending buffer side stem supporting said face plate from the end platform, said face plate having an opening therethrough in alignment with the buffer side stem, said opening being of a size to permit lengthwise withdrawal of said stem therethrough; and a member fixed to said face plate and interposed between the front end of the buffer side stem and said face plate at the opening of the latter, said member being of a size to block said opening and prevent removal of the buffer side stem through said opening.

6. In a buffering mechanism for a railway car including an end platform, the combination with a buffer face plate having a vertical front wall; of a buffer side stem supporting said face plate from said platform, said front wall of the face plate having an opening therethrough in alignment with said side stem and being of a size to permit lengthwise withdrawal of the side stem therethrough; and a supporting bracket detachably secured to the front end of the side stem, said bracket abutting the inner side of said front wall and extending over the opening thereof to block said opening.

7. In a buffering mechanism for a railway car including an end platform, the combination with a buffer face plate having a vertical front wall; of a buffer side stem supporting said face plate from said platform, said front wall of the face plate having an opening therethrough in alignment with said side stem and being of a size to permit lengthwise withdrawal of the side stem therethrough; and a supporting bracket detachably secured to the front end of the side stem, said bracket abutting the inner side of said front wall, said bracket having a forwardly extending boss seated in the opening of said front wall.

8. In a buffering mechanism for a railway car including an end platform, the combination with a buffer face plate having a vertical front wall and upper and lower, rearwardly extending flanges; of a buffer side stem supporting said face plate from said platform, said front wall of the face plate having an opening therethrough in alignment with said stem and being of a size to permit lengthwise withdrawal of said stem therethrough; and a supporting bracket for said side stem engaged over the front end of said stem and having a wall portion interposed between the front end of said side stem and said opening and abutting the inner side of said front wall of the face plate, said bracket being secured to said stem.

9. In a buffering mechanism for a railway car including an end platform, the combination with a buffer face plate having a vertical front wall and upper and lower, rearwardly extending flanges; of a buffer side stem supporting said face plate from said platform, said front wall of the face plate having an opening therethrough in alignment with said stem and being of a size

to permit lengthwise withdrawal of said stem therethrough; a supporting bracket for the side stem abutting the inner side of said front wall and extending over the opening thereof; and a pivot pin connecting the buffer side stem to the face plate, said pin extending through the front end of said stem, said bracket, and the flanges of said face plate.

10. In a buffering mechanism for a railway car including an end platform, the combination with a buffer face plate having a vertical front wall and upper and lower, rearwardly extending flanges; of a buffer side stem supporting said face plate from said platform, said front wall of the

face plate having an opening therethrough in alignment with said stem and being of a size to permit lengthwise withdrawal of said stem therethrough; a supporting bracket having top and bottom, rearwardly extending arms engaged over the front end of the side stem, said bracket abutting the inner side of the front wall of the face plate at the opening thereof and extending across said opening; and a pin for detachably connecting the bracket and side stem to each other and to said face plate, said pin extending through the front end of said stem, the arms of said bracket, and the flanges of said face plate.

ROLAND J. OLANDER.
